UNITED STATES PATENT OFFICE

DANIEL M. GRAY AND JOHN J. WILLIAMS, OF WHEELING, WEST VIRGINIA, ASSIGNORS
TO HAZEL-ATLAS GLASS CO., OF WHEELING, WEST VIRGINIA, A CORPORATION OF
WEST VIRGINIA

APPARATUS FOR CASTING ZINC SLABS AND THE LIKE

Application filed October 27, 1928. Serial No. 315,516.

In the casting of slabs of zinc as well as other metals it is desirable that the metal forming the slab be as nearly pure as is possible under practical working conditions in the factory. Even more desirable is the prevention of blow-holes or gas holes in the finished slabs, since these defects give rise to considerable difficulties in the working of the material when it is being formed into sheets 10 as a step in the process of making bottle caps or like articles.

An object of the present invention, therefore, resides in the provision of an apparatus and method of casting slabs of metal in a partial vacuum so as to eliminate the blow-holes or the like heretofore present in such castings.

A further object of the invention consists in the provision of a novel apparatus by means of which the molten metal is drawn directly from a point substantially midway between the top and bottom of the molten metal in the pot or furnace, thereby avoiding the entrance into the mold of impurities generally found adjacent the bottom of the pot or the 25 slag or dross which may be floating on the surface of the molten metal.

A still further object of the invention is to transfer the molten metal from the pot or crucible directly to the casting mold without 30 coming in contact with the atmosphere, thereby avoiding any possibility of a partial oxidation of the metal prior to its entering the mold.

Another object of the invention resides in 35 the provision of such an apparatus which is relatively simple and inexpensive in construction and which is so designed as to apply a vacuum in the most expeditious manner to produce the desired results.

40 Prior attempts have been made to cast metal slabs and the like in vacuo, but such devices have not gone into general use because of serious defects in the principal of operation as well as for various other reasons 45 which are well known to those skilled in the art.

While the present invention about to be described in detail is more particularly concerned with the casting of zinc slabs it will be 50 readily apparent that both the process and

apparatus are also well adapted to the casting of other metals.

In the drawings:

The figure is a side elevational view of a furnace in assembled relation with the vacuum apparatus and the casting mechanism, certain of the parts being shown in section. 55

Referring to the accompanying drawing more specifically, the numeral 1 designates the forward end of a pot or furnace in which 60 the molten zinc is prepared for casting. Adjacent the pot 1 is mounted the casting mechanism which is designated generally by the numeral 2, and comprises a table 3 mounted for rotation on a circular track 4. Supported on the table 3 are a plurality of inclined casting molds 5 which are of substantially air-tight construction and supported by means of plates 6 and braces 7 and 8. 65

As will appear from an inspection of the 70 drawing, the molds 5 are formed of two hinged sections, and are longitudinally adjustable along the supporting plates 6 by means of screws 9 which are threaded into sockets 10 on the table 3 and have their upper 75 ends in engagement with the lower ends of the molds 5. Handles 9' are fixed to the screws 9 for conveniently operating them. These molds, as already mentioned, are of substantially air-tight construction, and are 80 provided at their upper ends with necks 11 having flanges 12 which are adapted to form a ground joint with the vacuum system about to be described.

For the purpose of withdrawing the molten 85 metal from a point substantially midway between its top and bottom surfaces a pipe 13 is supported by any conventional means in a partly submerged position on the pot 1. This pipe 13 forms part of a conduit 15 leading to 90 a vacuum pump 16 and which conduit is provided with an air valve 17. The conduit 15 is provided with a branch pipe or conduit 18 for cooperation with the molds 5 and is also provided with a vacuum tank or trap 19 which 95 serves to prevent any liability of molten metal being drawn through the conduit to the pump 16. In this connection it may be mentioned that the conduit 15 extends vertically above the surface of the molten metal in pot 1 to 100

a distance of at least 60" thereby avoiding, under ordinary conditions, any possibility of the metal reaching the horizontal portion of the conduit.

5 Branch conduit 18 is provided with a circular flange 20 corresponding to the flange 12 on each of the molds 5 and is provided with a ground seating surface or with a packing so as to provide an air-tight joint with 10 the neck of a mold when clamped thereto by means of suitable clamps such as depicted on the drawing and designated by numeral 21. It will, of course, be understood that each of the molds 5 is brought successively to conduit 18 and clamped in position for the casting operation, and that the mold may be adjusted longitudinally by its screw 9 to the desired extent.

20 In order to avoid any possibility of the molten metal "freezing" in pipe 13 when the device is first put in operation and before the conduit has become sufficiently heated, a burner or heater 22 is placed around this pipe and supplied with proper fuel by means of a 25 pipe line 23; the burner being supported by a bracket 14.

25 In the operation of the device the molten metal is, of course, first prepared for casting and one of the molds 5 then connected up 30 to the vacuum system as indicated on the drawing. The vacuum pump 16 is then started and in addition to withdrawing air from the conduit 15 and mold 5 also serves to remove dissolved gases in the molten metal as 35 the latter rises in the pipe 13. This molten metal is drawn from the intermediate layers in the pot 1 and is therefore free of impurities such as are normally found on the bottom of such pots or floating upon the surface of the 40 molten metal. The point at which the metal flows over from conduit 15 into pipe 18 is about 50" above the surface of the molten metal, and inasmuch as a vacuum of 27" of mercury is capable of lifting a column of 45 molten zinc approximately 54", it will be apparent that the entire apparatus including the mold 5 will be exhausted to a vacuum of approximately 25" before the level of the zinc in pipe 13 reaches the branch conduit 50 18. Hence as the metal flows through conduit 18 down into mold 5 it will enter a vacuumized chamber thereby avoiding any possibility of entrapping air and forming blow holes in the finished product. When the mold 55 is filled the pump 16 is shut off or opened to atmosphere by valves 17, thus allowing the metal in pipe 13 to return to the pot. A small amount of the molten metal may remain in conduit 18 above the mold 5 when 60 the latter is released from its connection with the branch conduit, but such material may readily be caught in a trough and allowed to flow back to the pot. The filled mold is wheeled away and a new one brought up to 65 the casting station by the rotation of the table

3, so that the procedure may be repeated indefinitely while the supply of molten metal continues.

From the foregoing description of the apparatus and the method of operation, it will be obvious that the molten metal is transferred from the pot to the mold without contact with the atmosphere, thus avoiding any oxidation of the metal in the casting operation. It will also be noted that the transfer 75 of impurities from the pot to the mold is avoided, and that by reason of casting in vacuo the formation of gas and blow holes in the finished casting is greatly reduced if not entirely eliminated.

80 In accordance with the patent statutes we have described what we now believe to be the best embodiment of the apparatus for and the method of casting metal slabs, but it is to be understood that both the drawing and description are intended merely as illustrative of the invention and that the invention is susceptible of various changes without departing from the spirit of the invention.

85 Having fully described our invention, what we claim as new and desire to secure by Letters Patent is:

1. Casting apparatus for metal slabs, including a furnace for the molten metal, a substantially air-tight mold adjacent said furnace, a source of vacuum, communicating conduits leading from the source of vacuum to said furnace and mold, and a heater associated with one of said conduits.

2. Casting apparatus for metal slabs, including a furnace for the molten metal, a substantially air-tight mold adjacent said furnace and extending to a point located at a substantial distance above the surface of the metal in the furnace, a source of vacuum, a conduit leading from the source of vacuum downwardly and extending into the metal in said furnace, a branch conduit associated with said first-mentioned conduit, and means for forming a substantially air-tight connection between said branch conduit and said mold.

3. Casting apparatus for metal slabs, including a furnace for the molten metal, a substantially air-tight mold adjacent said furnace, a source of vacuum, communicating conduits leading from said source of vacuum to said furnace and said mold, and a trap for molten metal associated with one of said conduits.

4. Casting apparatus for metal slabs, including a furnace for the molten metal, a substantially air-tight mold adjacent said furnace, a source of vacuum, a conduit leading from the source of vacuum to said furnace, a branch conduit communicating with said first-mentioned conduit at a point substantially 50" above the plane of the surface of the molten metal, and means for connect- 130

ing the end of the branch conduit with the mold.

5. Casting apparatus for metal slabs, including a furnace for the molten metal, a substantially air-tight mold adjacent said furnace, a source of vacuum, a conduit leading from the source of vacuum and terminating in said furnace at a point substantially midway between the bottom of said tank and the surface of the molten metal, and a branch conduit leading from said first-mentioned conduit to said mold.

10 6. Casting apparatus for metal slabs, including a furnace for the molten metal, a substantially air-tight mold adjacent said furnace, a source of vacuum, a conduit leading from the source of vacuum to said furnace, a branch conduit leading to said mold, and means for adjusting the position of the mold with respect to its conduit.

15 7. Casting apparatus for metal slabs including a furnace for the molten metal, a substantially air-tight mold adjacent said furnace, a vacuum tank, a pump associated therewith, a conduit leading from said tank to the furnace, a branch conduit connected to the first-mentioned conduit at a point higher than the level of the metal in the furnace and leading to the mold.
